GAME DEVICE

Michael Ombrello, New York, N. Y.

Application August 18, 1938, Serial No. 225,645

1 Claim. (Cl. 273—97)

This invention relates to a novel game device of a so-called sword and ring type, and the object is to provide an imitation wooden or equivalent sword with a scoring target flexibly suspended 5 on the end thereof, whereby to provide a simple arrangement calculated to promote amusing skill and pastime in attempting to spear the elusive target.

More specifically, the preferred embodiment of 10 the invention comprises a somewhat pointed stick having a crosspiece at the inner end forming a guard, there being a string attached to the free end of the stick and said string carrying on its opposite end an apertured target or equivalent 15 device, whereby to permit said device to be cast into the air by a flipping movement of the stick so that the user may try his skill at spearing the target.

Considered from a specific structural stand- 20 point, novelty is attached to the unique target. The target could be of other construction but is broadly an apertured element in the form of a ring or plate, the different distinguishable apertured portions thereof having varying scoring 25 values, whereby to promote greater interest than would be acquired through the use of a single bull's-eye or ring.

Other features and advantages may become ap- 30 parent from the following description and drawing.

In the drawing:

Figure 1 is a perspective view of the game device as constructed in accordance with the specific principles of this invention.

Figure 2 is a section which may be said to be taken approximately on the plane of the line 2—2 of Figure 1.

Figure 3 is a detailed section in elevation, the section being somewhat on the plane of the line 40 3—3 of Figure 1.

Figure 4 is a detail view showing a modification of the construction of the spearable target.

In the drawing, in Figure 1 the so-called sword is denoted by the numeral 4. This comprises a 45 staff or stick generally cylindrical in cross sectional form and tapered so that the shank portion 5 may function as a spear and the opposite end portion 6 as a hand-grip. At the juncture of the shank and hand-grip is an aperture and passed 50 through this is a transverse round 7, this being nailed or otherwise fastened intermediate its ends as at 8 to form a hand-guard or shield.

As before indicated, the elusive and pendulous 55 style target, according to this conception will vary in form and configuration. One style is shown

in Figure 1, and another modification in Figure 4, although the principle of construction may be brought into effect by other equivalent constructions. Referring for example, to Figure 3, it will be observed that the target 9 is here in the form 5 of a flat plate whose outline or configuration is such as to represent a flounder. Any other animal, fish, bird or the like could be utilized with this suggestion in mind. The target is attached to one end of the suspension string 10 10. The opposite end of the string is formed with a loop 11 and this is secured by a headed fastener 12 into one side of the stick 6 at the extreme outer end thereof. By securing the loop on the side instead of in the extreme tip 15 or outer end as is ordinarily done, there is less strain on the fastening and less likelihood of the fastening becoming accidentally displaced or the cord readily ripped off by shearing strain.

Considering again the target, the flat plate is 20 provided with a main large opening as at 13, and a series of smaller openings properly graduated and differentiated by the numerals 14 and 15, respectively. The hole 13 may be marked to count one score, the hole 14 another score and the 25 hole 15 a different score and so on. The smaller the hole, the larger the score, as is obvious. In practice, any suitable indicia or markings (not shown) may be employed to differentiate these variable tallying holes or apertures. Conse- 30 quently, it is believed that this floating target idea in a spearing and piercing game of this type, is unique.

Referring to the modification seen in Figure 4, the target is differentiated by the numeral 16. 35 This is a simple wire or similar ring 17 having an eye at 18. The string 10 is attached to the eye at the point 19. By using this eye connection the point of anchorage of the string is such that it is not apt to be chafed by the passing of 40 the sword through the perimeter portion of the ring 17. In other words, if the cord were tied around the ring direct without the eye connection, its life would be materially shortened. It is to be observed too that the auxiliary ring 20 within the 45 limits of the main ring 17 is relatively small and attached thereto by a stem or the like 21. The two rings 17 and 20 have different scoring values corresponding to the apertures 13 to 15 in the target shown in Figure 1. Thus, in a generic 50 sense the units 9 and 16 are targets. Also they are targets having multiple selectively spearable openings or apertures. Then too, the different apertures thus speared have variable predetermined scoring value.

In practice, it is obvious that the target is literally tossed in the air while holding the hand-grip 6 and by properly manipulating the sword, the desired pendulous swing or action is provided. 5 Then by utilizing suitable skill, the user attempts to spear either one of the rings or to pass it through one of the apertures in the particular style of target utilized. The participants, by counting the scores thus made, can develop an 10 amusing skill invoking pastime.

It is thought that the description taken in connection with the drawing will enable a clear understanding of the invention to be had. Therefore, a more lengthy description is thought unnecessary. 15

While the preferred embodiment of the inven-

tion has been shown and described, it is to be understood that minor changes coming within the field of invention claimed may be resorted to if desired.

I claim:

As a component part of a game device of the class described, a flexible suspension cord, a target comprising a main ring having an eye formed on its outer peripheral edge, said cord being attached at one end to said eye, an auxiliary ring arranged eccentrically within the limits of the main ring and in a plane therewith, said auxiliary ring having an attaching stem connected to the inner peripheral edge of said main ring at a point diametrically opposite to said eye. 10 15
